PACIFIER FOR BABIES

Gilbert P. Proctor, 325 31st St., Snyder, Tex.

Continuation of design application Ser. No. 78,075,
Jan. 6, 1964. This application Aug. 6, 1964, Ser. No.
81,186

Term of patent 14 years

(Cl. D83—8)

FIG. 1

FIG. 2

FIG. 1 is a front perspective view of a pacifier for babies showing my new design;

FIG. 2 is a rear perspective view thereof.

This is a continuation of application Ser. No. D. 78,075, filed January 6, 1964, and now abandoned.

I claim:

The ornamental design of a pacifier for babies, as shown and described.
